UNITED STATES PATENT OFFICE.

NICHOLAS HORN, OF PATERSON, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,343,509.

Specification of Letters Patent. Patented June 15, 1920.

Application filed November 6, 1917. Serial No. 200,477.

To all whom it may concern:

Be it known that I, NICHOLAS HORN, a citizen of the United States, residing in Paterson, in the county of Passaic and State of New Jersey, have invented certain new and useful Improvements in Typewriting-Machines, of which the following is a specification.

This invention relates to an improvement in typewriting machines, and more particularly to paper-fingers for gripping the work-sheet to the platen.

The paper-fingers are adjustably mounted so as to swing into and out of engagement with the platen, and are also adjustable lengthwise of the platen, so as to accommodate sheets of different widths. In order to hold the paper-fingers tight on the platen, when in their active positions, strong springs are used. These springs when effective prevent the easy adjustment of the paper-fingers lengthwise of the platen. Provision is therefore made in the present case for relieving the relatively moving parts of the thrust of the spring when it is desired to adjust either paper-finger. Thus there will be little or no tension tending to create excessive friction holding the fingers against sliding adjustment. This arrangement includes a rod parallel to the platen on which a sleeve for each finger is splined. Each paper-finger is rotatably mounted on its sleeve. When it is in its active position, each paper-finger is forced toward the platen by a spring controlling a pair of rollers, which are eccentrically located in a pair of cavities provided in the corresponding sleeve. When it is desired to swing either finger away from the platen for longitudinal engagement along the rod, the pressure of the spring is relieved by an eccentric cam, which forces both arms of the spring outwardly to relieve the pressure on the rollers. This enables a paper-finger as a whole to be readily slid along the rod, as the tension which the spring places on the sliding connection between the rod and sleeve is relieved.

Other features and advantages will hereinafter appear.

In the accompanying drawings,

Figure 1 is a perspective view, showing the left-hand finger as in its active position in engagement with the platen.

Fig. 2 is a vertical section, taken from front to rear, showing the right-hand finger in its active position in engagement with the platen.

Fig. 3 is an enlarged detail section, taken longitudinally of the rod or shaft on which the paper-fingers are mounted.

Considering more specifically the particular parts of the invention as embodied in the form shown in the drawings, the platen 1 is mounted to rotate on a carriage 2. The platen 1 is rotated in the usual manner either by knobs 3 or line-space mechanism 4. For the purpose of holding the work-sheet on the platen at the printing point, indicated at 5 by a type-bar, there are provided a pair of paper-fingers 6 facing inwardly toward each other. A left-hand paper-finger is shown in Fig. 1 and a right-hand paper-finger is shown in Fig. 2. These paper-fingers are slidably and pivotally mounted on a rod or shaft 7, which is secured at its ends in the frame of the carriage 2. Each paper-finger includes a roller 8, which, when the paper-finger is in action, engages with the platen 1, or at least with the work-sheet carried by the platen. The roller 8 is mounted in a spring bracket 9, which, in turn, is supported by an inwardly-turned flange 10 of an arm 11. The arm 11 is formed integral with a channel-shaped frame 12, having openings through which the shaft 7 extends.

The channel 12 does not engage directly with the shaft 7, but is mounted on a sleeve 13 located between the shaft and the channel 12. The sleeve 13 is provided with a spline or key 14, which extends into slots 15 and 16 on the sleeve and shaft, respectively. This forms a sliding connection between the sleeve and the shaft, and as the channel 12 is pivoted on the sleeve 13, the paper-finger 6 has a sliding and pivotal mounting with respect to the shaft 7. The channel 12 and the parts carried thereby are held against slipping off the ends of the sleeve 13 by the turning up of the ends of the key or spline 14 at 17 and 18.

To hold the roller 8 in tight contact with the platen 1, there is provided a strong bow-spring 19, which has a pair of arms 20 and 21 extending on opposite sides of the sleeve 13. These arms 20 and 21 engage rollers 22 and 23 eccentrically located in cups or

- sockets 24 and 25, provided in the sleeve 13. The rollers 22 and 23 are mounted in slots 26 provided in the arm 11 of the paper-fingers 6. This enables the rollers 22 and 23 5 to move toward and from the axial center of the shaft 7. The arms of the bow-spring 19 are arched at their points of engagement with the rollers 22 and 23 to form sockets and so that they force the rollers 22 and 23 10 to tend to seat themselves properly in their sockets. But as the pressure roller 8 comes into engagement with the platen 1 before this can take place, there is always a force exerted by the paper roller 8 on the platen 15 1. This force reacts on the spline connection 14, 15 and 16 between the sleeve 13 and the shaft 7, so that each paper-finger is locked against accidental displacement longitudinally of the shaft 7 and the platen 1.
- 20 The force holding the paper roller 8 tight on the platen 1 and preventing accidental displacement of the paper-finger as a whole, would also interfere with the adjustment of the paper-finger if it were desired to shift the 25 same to accommodate work-sheets of different widths. To prevent this, the pressure of the bow-spring 19 on the rollers 22 and 23 is relieved when necessary to shift a paper-finger. For this purpose, there is provided a 30 finger-piece 27, which is pivoted at 28 to the cross-piece of the channel 12, and has formed thereon a double eccentric cam 29 engaging with extensions 30 of the arms 20 and 21. This cam 29 lies between the extensions 30, so that when the finger-piece 27 is swung about its vertical pivot, it will 35 spread the arms 20 and 21, taking the pressure from off the rollers 22 and 23. The finger-piece can now be adjusted along the 40 shaft 7 either in active position in engagement with the platen 1, or in inactive position away from the platen without much frictional resistance between the sleeve 13 and the shaft 7. This is because of the fact 45 that the pressure of the spring tending to hold the paper-finger tight on the platen has been taken up by the cam 29.
- The particular form of the bow-spring 19 is seen by reference to Figs. 1 and 3. The 50 arms 20 and 21 have each three forks, the middle one of which forms the extension 30. These three forks are provided with the bends or curves engaging the rollers 22 and 23 at several points along their lengths; 55 thus a multiple spring of considerable strength is formed which exerts sufficient tension to hold the paper-finger in active engagement with the platen 1. The effective shifting of the relieving finger-piece 27 60 takes this tension entirely off of the shaft 7, and thus enables the paper-finger to be practically lightly pivoted and slidably mounted on the shaft 7. The bow-spring 19 is swingingly mounted, as seen in Fig. 65 3, by means of cones 31 engaging in pivot

openings 32, provided in the channel 12 of the paper-fingers.

The paper-fingers 6 are identical for the left and right sides of the platen 1, except that they face in opposite directions; that is to say, the flanges 10 extend inwardly from the arms 11 mounted on the outer sides of the channels 12. The fingers are adjustable toward each other on the shaft 7 to accommodate work-sheets of varying widths, and are adjusted pivotally with respect to the shaft 7 to shift between active and inactive positions.

It should be understood that the paper-finger may be relieved of the spring tension by moving the handle or finger-piece either leftwardly or rightwardly. Thus, when it is desired to move the paper-finger leftwardly, the finger-piece 27 is moved leftwardly about its pivot 28, until the paper-finger has been relieved of the spring tension, after which the handle moves bodily to move the paper-finger toward the left until the latter is adjusted to the proper position. When adjusting the paper-finger toward the right the action will be the same as above described, except that the movements of the finger-piece 27 and the paper-finger 6 will be in reverse directions.

I have preferably mounted the channel 1 or yoke 12 on the sleeve 13, and have provided the sleeve with sockets 24 and 25 in which the spring-pressed rollers 22 and 23 engage; but it should be understood that variations may be resorted to within the scope of the invention, and portions of the improvements may be used without others.

Having thus described my invention, I claim:

1. The combination with a platen, of a paper-finger for said platen, a shaft on which said finger is slidably and pivotally mounted, a sleeve splined on said shaft, spring means reacting between said sleeve and said finger for causing said finger to grip said platen, and also causing said sleeve to bind on said shaft, so as to prevent accidental movement of said finger, and cam means separately operated with respect to the sliding and pivotal movement of said finger for taking up the tension of said spring means, so as to relieve said shaft, said sleeve and said finger of the action and reaction thereof.

2. The combination with a platen, of a paper-finger for said platen, a support for said finger, a mounting member having a slidable but non-rotative connection with said support, and a rotative but non-slidable connection with said finger, said mounting member having a socket therein, a roller in engaging relation with said socket and having a guiding connection with said finger for determining its relative direction of movement, and means, including a resilient

member, normally tending to seat said roller accurately in said socket, said means being opposed by the engagement of said paper-finger with said platen, whereby said paper-finger will be normally under a pressure so as to tightly engage said platen.

3. The combination with a platen, of a paper-finger for said platen, a shaft on which said paper-finger is slidingly and pivotally mounted, a sleeve splined on said shaft having a socket therein, said sleeve being loosely interposed between said finger and said shaft, whereby said finger may pivot about said sleeve and about said shaft, a roller located in said socket and having a pin-and-slot connection with said finger, spring means tending to seat said roller accurately in said socket, opposed by the engagement of said paper-finger with said platen, whereby said paper-finger will be normally under a pressure so as to tightly engage said platen, and means for taking up the tension of said spring means so as to relieve said roller and the parts reacting therewith from the tension of said spring means, whereby said finger may be easily shifted along said shaft.

4. The combination with a platen, of a paper-finger for said platen, a shaft on which said paper-finger is slidingly and pivotally mounted, a sleeve splined on said shaft and interposed between said paper-finger and said shaft, said sleeve having a pair of sockets therein, rollers located in said sockets and connected to said paper-finger, and a bow-spring having arms extending on opposite sides of said sleeve and engaging said rollers tending to seat said rollers accurately in said sockets, so as to cause said paper-finger to grip said platen, the axis of rotation of said platen, the center of said shaft and the point of contact of said paper-finger with said platen being so relatively disposed that the movement of said paper-finger is obstructed before said rollers properly seat themselves in said sockets, whereby said bow-spring will normally exert a continuous pressure, holding said paper-finger in tight engagement with said platen.

5. The combination with a platen, of a paper-finger for said platen, a shaft on which said paper-finger is slidingly and pivotally mounted, a sleeve splined on said shaft and interposed between said paper-finger and said shaft, said sleeve having a pair of sockets therein, rollers located in said sockets and connected to said paper-finger, a bow-spring having arms extending on opposite sides of said sleeve and engaging said rollers tending to seat said rollers accurately in said sockets, so as to cause said paper-finger to grip said platen, the axis of rotation of said platen, the center of said shaft and the point of contact of said paper-finger with said platen being so relatively disposed that the movement of said paper-finger is obstructed

before said rollers properly seat themselves in said sockets, whereby said bow-spring will normally exert a continuous pressure, holding said paper-finger in tight engagement with said platen, and relieving means interposed between the arms of said bow-spring, so as to take up the tension thereof and thus relieve the tension between said sleeve and said paper-finger and said sleeve and said shaft, whereby said paper-finger may be easily adjusted along said shaft.

6. The combination with a platen, of a paper-finger for said platen, a shaft on which said paper-finger is slidingly and pivotally mounted, a sleeve interposed between said paper-finger and said shaft and splined on said shaft, locking means interposed between said sleeve and said paper-finger including a bow-spring pivotally mounted to move with said paper-finger and having arms extending on opposite sides of said sleeve, and means mounted to move with said paper-finger interposed between the arms of said bow-spring, so as to spread them to render said bow-spring ineffective.

7. The combination with a platen, of a paper-finger for said platen, a shaft on which said paper-finger is slidingly and pivotally mounted, a sleeve interposed between said paper-finger and said shaft, locking rollers interposed between said shaft and said paper-finger, a bow-spring having arms extending on opposite sides of said sleeve engaging said rollers to cause them to yieldingly lock said paper-finger relatively to said sleeve and to said platen, a cam interposed between the arms of said bow-spring and mounted to move with said bow-spring and said paper-finger, and means for rotating said cam, so as to control the activity and inactivity of said bow-spring and said locking rollers.

8. The combination with a platen, of a paper-finger for said platen, a shaft on which said paper-finger is slidingly and pivotally mounted, a sleeve splined on said shaft having a pair of sockets therein, a bow-spring mounted on said paper-finger having arms extending on opposite sides of said sleeve with bands to form sockets in register with the sockets of said sleeve, rollers eccentrically located in opposed sockets of said sleeve and said spring arms, normally tending to properly seat themselves, so as to cause said paper-finger to exert pressure on said platen, and means for spreading said spring arms, so as to increase the space in which said rollers are located, relieving the pressure between said rollers, said sleeve and said finger, and also between said sleeve and said shaft, whereby said finger may be easily adjusted.

9. The combination with a platen, of a paper-finger, a support on which said paper-finger is slidingly and pivotally mounted,

- spring means re-acting between said paper-finger and said support to exert a pressure on said platen, and a finger-piece pivotally mounted on said paper-finger adapted to adjust said paper-finger lengthwise of its support, said finger-piece having a movement substantially in the direction in which the adjustment of said paper-finger is to take place, so as to first relieve the strain of said spring means between said paper-finger and said support before the paper-finger is moved.
10. The combination with a platen, of a paper-finger for said platen, a support for said finger, a mounting member having a slidable but non-rotative connection with said support, and a rotative but non-slidable connection with said finger, means comprising a resilient member normally tending to rotate said finger about said mounting member in a direction such as to hold it in snug contact with said platen, a finger-piece, and means controlled by said finger-piece for taking up the tension of said resilient member and thus rendering the same ineffective upon said paper-finger, whereby said paper-finger may be easily adjusted relative to the support.
11. The combination with a platen, of a paper-finger for said platen, a support for said finger, a mounting member having a slidable but non-rotative connection with said support, and a rotative but non-slidable connection with said finger, said mounting member having a socket therein, a roller in engaging relation with said socket and having a guiding connection with said finger, for determining its relative direction of movement, means including a resilient member, normally tending to seat said roller accurately in said socket, said means being opposed by the engagement of said paper-finger with said platen, whereby said paper-finger will be normally under a pressure so as to tightly engage said platen, a finger-piece, and means controlled by said finger-piece for taking up the tension of said resilient member, so as to render it ineffective on said paper-finger, whereby said paper-finger may be easily shifted along said support.
12. The combination with a platen, of a paper-finger, a support on which said paper-finger is movably mounted so as to be adjustable axially of said platen, means, including a resilient member, normally exerting a holding pressure between said paper-finger and said platen, a finger-piece mounted on said paper-finger and relatively movable with respect thereto on application of pressure in the direction of adjustment of said paper-finger, and means, controlled by such relative movement of said finger-piece, for taking up the tension of said resilient member, so as to render it ineffective on said paper-finger, whereby, on application of pressure to said finger-piece in the direction of adjustment of said paper-finger, it will first be moved relatively to said paper-finger, so as to render said resilient member ineffective and, on continuation of the application of such pressure in the same direction, said finger-piece may be moved to an adjustable position free from opposing influence by said resilient member. 7
13. The combination with a platen, of a paper-finger, a support on which said paper-finger is movably mounted, so as to be adjustable axially of said platen in either of two directions, resilient means normally exerting a holding pressure between said paper-finger and said platen, a finger-piece mounted on said paper-finger and relatively movable with respect thereto on application of pressure in either of its two directions of adjustment, and means, controlled by such relative movement of said finger-piece, for taking up the tension of said resilient member, so as to render it ineffective on said paper-finger, whereby, on application of pressure to said finger-piece in either of its two directions of adjustment, it will first be moved relatively thereto so as to render said resilient member ineffective, and on continuation of the application of such pressure in the same direction, said paper-finger may be moved to an adjusted position free from opposition by said resilient member. 80 85 90 95
